Primary Examiner — Garth Rademaker*(74) Attorney, Agent, or Firm* — SAIDMAN DesignLaw Group(57) **CLAIM**

The ornamental design for an automobile tire, as shown and described.

DESCRIPTION

FIG. 1 is a front perspective view of an automobile tire tread showing my new design;

FIG. 2 is a front view thereof, the top plan and bottom plan views being identical thereto;

FIG. 3 is a rear view thereof;

FIG. 4 is a left side view thereof; the right side view being identical thereto;

FIG. 5 is an enlarged fragmentary front view, showing section 5-5 of FIG. 2; and,

FIG. 6 is a cross-sectional view thereof, taken along line 6-6 and in the direction of arrows in FIG. 5.

The broken lines depict environmental subject matter only and form no part of the claimed design.
